METHOD AND APPARATUS FOR PRODUCING
IMITATION PIGSKIN ARTICLES

Samuel A. Richardson, Burlington, Iowa, assignor to Wells Lamont Corporation, a corporation of Minnesota

Application September 3, 1941, Serial No. 409,432

13 Claims. (Cl. 41—24)

This invention relates to the production of articles of imitation pigskin, especially leather gloves. The invention is particularly concerned with the so-called "pigtexing" treatment by which the article leather, comprising calfskin or other smooth-surfaced skin is provided with small pore-like openings in predetermined design to simulate the hair openings of genuine pigskin.

The general aim of the invention is to provide an improved method and an improved apparatus for producing imitation pigskin articles having a permanent well defined pore-like pattern in the article skin, and without objectionably stretching or otherwise distorting the material in the course of the "pigtexing" treatment.

It is a further important object to provide a method and apparatus of such character that the "pigtexing" treatment will be so carried out in the course of manufacture of the leather article that the imitation pigskin design after production will not subsequently be mutilated or distorted in other operating stages in the production of the finished imitation pigskin article.

Various practices have heretofore been tried in the production of imitation pigskin gloves. According to one practice large sheets of smooth-surfaced skin are fed between a pair of power-driven rolls, one of which is provided with pin-like elements adapted to impress pore-like openings in the leather. Thereafter the imitation pigskin so produced is cut up into various glove parts. This practice is subject to two objections. First, the use of the coating rolls results in an undesired and unnecessary stretching of the leather incident to the "pigtexing" operation and the design produced is not as distinct and perfect as desired. The further objection is that the leather undergoes further stretching in the subsequent stage of stamping out the glove parts which further tends to obscure and distort the pigskin design.

According to a further practice, use is made of a flat upper platen containing suitable pins for producing a pigskin design, and a coating stationary, smooth, lower platen, the upper pin platen being reciprocable to and from operative position relative to the other. The leather to be treated is fed step by step between the platens by feed means such as a traveling belt, and the pigskin design imparted progressively to successive areas of the leather sheet or sheets. The use of coating flat platens for producing the pigskin design at least partially eliminates the stretching experienced when employing coating rolls according to the practice first mentioned. On the

other hand, the use of coating flat platens necessitates the application of a relatively high operating pressure if the platens have any measurable size, and for this reason it has been found practically expedient to limit the coating platens to relatively small dimensions, only several inches wide and of about nine inches in their greatest dimension, in order to limit the size of the machine and the operating pressure required, with the result that only small areas of leather, less than the length of a glove body blank, can be treated in each operating stage. Under such conditions the leather which is progressively fed between the platens emerges either with overlaps or gaps between, the patterns produced in successive stages.

With a view of overcoming certain of the difficulties with the last-mentioned practice, it has been proposed in Straus Reissue Patent No. 19,402, dated December 18, 1934, to first cut the leather into small blanks for the glove parts and secure them by adhesive to a length of paper for progressive feeding through the relatively reciprocating small platens.

While this improved practice avoids stretching of the leather subsequent to application of the pigskin pattern by reason of the cutting of the glove parts preliminary to the formation of the design, it has not proved very practical in commercial production of gloves because of the difficulties in constructing a machine which will produce proper cooperation of the coating flat platens and perfectly apply repetitions of the pigskin design to successive areas of the leather when employing small platens. Further, the cementing of the various glove parts to the paper preliminary to pigtexing, and the subsequent removal of the parts from the paper after the treatment is over constitute additional steps in the manufacturing process which are necessarily objectionable.

The present invention eliminates completely, or substantially so, the objections to the various prior practices referred to by utilizing a different operating procedure and a different form of machine. According to the invention large smooth-surfaced skins are first reduced to relatively small pieces, preferably being stamped into individual blanks for various glove parts so that any stretching incident to such operation will precede the pigtexing treatment. The leather pieces, preferably a number of them at one time, are then laid flat on a platen having upstanding sharp-end pins suitably formed and arranged in the platen to produce pore-like openings of tapering cross-

section substantially through the thickness of the leather to simulate genuine pigskin. The pointed ends of the pins tend to engage the face of the leather throughout its area, and because of their close arrangement resist stretching of the leather. A blanket of puncturable material such as kraft stencil paperboard is then superposed on the leather, and a smooth-surfaced pressure roller is moved forward and back on top of the stencil-board to force the platen pins into the leather. When this operation is completed the leather will have a clear-cut, well defined uniform pigskin design pattern, and the leather will be ready for the next manufacturing stage which ordinarily will be the assembling of the individual blanks into a complete glove.

The machine for carrying out the "pigtexing" operation just described is so designed as to prevent relative slippage between the pressure roller and the pin platen. This feature in conjunction with the contact of the sharp ends of the platen pins with the leather serves to resist stretching of the leather in the course of the pigtexing treatment. The blanket which is superposed on the leather serves to enable the tapering openings to be produced throughout the entire thickness of the leather for permanency of the design, and without injury of the pointed ends of the pins through contact with the surface of the pressure roller. The blanket further serves to prevent the leather from being drawn up off the platen pins by the roller. Arrangement is made whereby the blanket is automatically laid down and taken up in the course of movement of the roller so that the same does not require the attention of the operator.

The various features and advantages of the invention will become more apparent from the following detailed description and the drawings of a preferred embodiment of the machine which constitutes an important part of the invention. In the drawings:

Fig. 1 is a side view of a machine for producing imitation pigskin incident to the manufacture of leather articles;

Fig. 2 is a top plan view corresponding to Fig. 1;

Fig. 3 is an end elevation looking from the left of Fig. 1;

Fig. 4 is an enlarged longitudinal section of the same machine;

Figs. 5 and 6 are side and top views of one of the individual pigtexing pins, the same being greatly enlarged over actual size; and

Fig. 7 is a fragmentary view of the platen shown in Fig. 2, indicating the arrangement of the pins to produce an imitation pigskin design.

The inventive machine includes a platen 10 of such size, preferably, as to receive the cut blank parts of a single glove for pigtexing them all in a single operation. Of course, by increasing the dimensions of the platen it may be made of such capacity as to handle the pieces for a plurality of gloves at one time. Cut leather sheets may also be treated in the machine before shaping thereof into an article blank or blanks where such shaping can be carried out subsequently by stamping or other method of cutting which will not produce objectionable stretching of the leather after formation of the imitation pigskin design therein.

The top of the platen 10, as indicated in Fig. 2, is provided with a series of upstanding perforating pins 11. As shown in Figs. 5 and 6, such pins have an elongated base somewhat of the shape

of a tear drop and taper upwardly to a pointed upper end longitudinally offset from the center of the base. The tapering upwardly extending edges are preferably made sharp so as to actually cut openings in the leather rather than merely form pressed indentations therein. In height the pins will approximate the thickness of the leather to be treated, and as hereafter pointed out provision is made whereby the operating depth of the pins may be varied for leather of various thicknesses.

As best shown in Fig. 7, pins 11 are arranged on platen 10 in an organized design as a series of clusters to approximate the arrangement of the hair openings in genuine pigskin.

A table 12 having side rails 13 and 14 supports platen 10 and the other operative parts of the machine. Platen 10 is supported between side rails 13 and 14 by means of a series of cross frame members 15. Threaded through the latter members are vertically adjustable bolts 16 connecting at their upper ends with securing fastenings on the underside of the platen. Through adjustment of the various bolts the platen may be raised or lowered relative to side rails 13 and 14.

A truck having opposite frame portions 17 is provided for reciprocatory movement longitudinally of the table. Upper pairs of rollers 18 having peripheral ribs fitting in grooves in the top of rails 13 and 14 support the truck for longitudinal movement and prevent lateral shifting and wobbling thereof. Further pairs of rollers 19 are mounted on the truck frame member 17 to engage the undersides of rails 13 and 14 so that the truck is held for movement in a fixed horizontal path.

Rotatably mounted in the truck is a pressure roll 20 of approximately the same width as the platen 10 adapted to cause penetration of the leather by platen pins 11. Secured in the table between side rails 13 and 14 and platen 10 are toothed rack bars 21 engaged by gear wheels 22 rigid with the opposite ends of roller 20 on its supporting shaft 23. For purposes of safety hood members 24 are secured to the truck sides 17 to overlie gears 22 and the upper truck supporting rollers 18.

Through coaction of gears 22 with racks 21 the truck may be moved forward and backward lengthwise of the table with simultaneous rotation of pressure roll 20. As shown in Fig. 4 the pressure roll will have a starting position S slightly beyond the left end of platen 10 so as to leave the entire surface area of the platen exposed to receive the leather to be treated, and will reciprocate between such position and a forward end position F at the right end of the platen. The speed of rotation of pressure roll 20 will correspond exactly to its component of lengthwise movement so that there will be no relative slippage between the surface of the roll and the platen during the course of operation, with the result that stretching of the leather is greatly minimized.

In the present embodiment of the machine hand power is employed for operation. To this end a handle 25 is secured to pressure roll 20. By properly selecting the diameter for the pressure roll, movement of the handle through a relatively short arc will serve to propel the pressure roll and its truck from one end position to another and back to its starting position through reverse movement of the handle. Where using hand power in this manner it is preferable that the

roll be of a diameter such that approximately one-half of its perimeter, more or less, measures and coacts with the full length of the supporting platen 10.

As best shown in Figs. 1 and 2, opposite spring stops 28 and 29 engageable with coacting wings 30 on the truck side 17 serve to cushion the truck as it reaches its opposite end positions. As shown, such springs may be mounted on supporting rods 26 secured to the table outwardly of side rails 13 and 14.

Pressure roll 20 preferably is formed with a smooth bronze operating surface to oppose the perforating pins 11 as the roll moves over platen 10. Through adjustment of the vertical height of platen 10 by means of bolts 16, the surface of the roll may be maintained with a slight clearance from the pointed tops of the pins since the roll is supported independently of the platen by side rails 13 and 14.

It is desirable to use a backing blanket between the leather and pressure roll 20. Such blanket is preferably inelastic, and it has been found in practice that flexible kraft stencil-board is very satisfactory for the purpose. While such blanket may merely be laid by hand over the leather after applying the leather to the platen, it is more convenient and advantageous to arrange the blanket to be automatically laid down and taken up by the machine in the course of its operation.

As best shown in Figs. 2 and 4 the blanket 31 is detachably secured at its left end by a clamp member 32 yieldingly connected by springs 33 to the left end of table 12. Such blanket is of a length to extend slightly beyond the right end of platen 10, and the second end of blanket 31 is detachably secured by clamp member 34 to the periphery of pressure roll 20 at a circumferential point thereof beyond the contact of the roll with the platen in the forward end position F. With such arrangement blanket 31 is laid by the pressure roll during its forward movement from positions S to F, and is wound up on the roll during the return movement of the roll. One function served by the blanket is to prevent the leather from being lifted from the platen and taken up with the surface of the roll. It is obvious in this connection that if the leather is lifted from the pins of the platen after the pins penetrate the leather to form a design in movement from left to right, the openings formed may be thrown out of registry with the pins by shifting of the leather so that upon the return movement of the roll from right to left the pins will engage different points of the leather and produce a second set of openings giving a defective design.

It will be apparent from Figs. 1, 2 and 4 that the table 12 is longer than necessary at its left end for proper operation of pressure roll 20 in relation to platen 10. If desired platens of greater length may be employed with accompanying change in position of the left truck end stops 29, but in such event other operating means than handle 25 should be employed. It is convenient to have blanket 31 extend to the left substantially beyond the starting position S of pressure roll 20 so as to facilitate replacement. In such event a supporting plate 35 may, as shown, be mounted in the frame to overlie blanket 31 beyond the left end of platen 10. The yielding support of the left end of the blanket provided by springs 31 tends to keep the blanket tight during operation and also to prevent tearing thereof.

The "pigtexting" treatment of article leather

will now be described in conjunction with the machine.

The smooth-surfaced leather for the articles will preliminarily have all of the ordinary finishing operations performed thereon so that no treatment need be effected after "pigtexting" which by stretching or otherwise might impair the imitation pigskin design. Sheet leather will be cut in suitable form to fit the machine. For the manufacture of gloves the leather will preferably have the blanks for the various glove parts stamped therefrom inasmuch as this operation ordinarily produces a stretching of the leather.

The leather is now ready for the "pigtexting" treatment and will be laid flat upon the pointed ends of pins 11 of platen 10. In Fig. 2 the cut pieces for one complete glove are shown in operative position on the platen. Such pieces constitute the main body blank A, thumb piece B, and fourchettes C, D and E. The tops of the pins engage the leather at a great multiplicity of points, and because of their sharpness serve to resist stretching and shifting of the leather relative to platen 10 incident to the "pigtexting" treatment.

Blanket 31 is then laid over the leather and pressure is applied to force the leather down on the pins, these operations being performed simultaneously upon movement of pressure roll 30 to the right from position S to position F. To better fix the imitation pigskin design and assure its permanency, pressure roll 20 is moved back to the left to position S with the leather still in position on platen 10. Blanket 31 has served to prevent the leather from being lifted from the pins during the preliminary passage of pressure roll 20 thereover during movement to the right so that the pins engage with the same parts of the leather during the return movement of the roll. There is therefore no danger that the pattern will be mutilated due to the double rolling operation.

The pigtexting treatment is now complete and the leather is removed from platen 10 and formed into a complete article. While the process has been illustrated in connection with the manufacture of gloves, it is obvious that it is applicable to the manufacture of other leather articles where an imitation pigskin design is appropriate.

I claim:

1. The method of making an imitation pigskin glove which includes preliminarily cutting sheet leather into glove parts, applying the cut glove parts to the points of a flat series of upstanding sharp-pointed impression pins arranged to simulate a pigskin design, rolling the glove parts while supported by the pin points to depress the leather upon the pins, removing the glove parts from the pins, and assembling the parts into a glove.
2. The method of making an imitation pigskin article which includes applying to the points of a flat area of upstanding sharp-pointed impression pins, arranged to simulate a pigskin design, leather cut to smaller size than the area defined by the pins, rolling the leather while supported by the pin points to cause the leather to be pierced by the pins, removing the leather from the pins and forming the leather into the finished article.
3. The method of making an imitation pigskin article which includes cutting sheet leather to article form before applying the pigskin design to prevent any stretch imparted to the leather during cutting from marring the design sub-

sequent to its formation, applying the cut leather to the points of a flat area of upstanding sharp-pointed impression pins arranged to simulate a pigskin design, reciprocating a pressure roll across the leather while so supported to cause the leather to be pierced by the pins, removing the leather from the pins and forming the leather into the article.

4. The method of making an imitation pigskin article which includes applying to the points of a flat area of upstanding sharp-pointed impression pins arranged to simulate a pigskin design article leather cut to smaller size than the area defined by the pins, reciprocating a pressure roll across the leather while retaining the leather by a blanket against being withdrawn from the pins by the roll, removing the leather from the pins, and forming the leather into the article.

5. The method of forming an imitation pigskin design in leather which includes preliminarily applying a piece of leather to the points of a mass of rigid sharp-pointed pins arranged to simulate a pigskin design and securing initial engagement of the leather by the points of the pins throughout their common area, then moving a press roll progressively across the piece of leather to press the same inwardly on the area of pins and thereby form a pigskin design in the leather, and thereafter removing the leather from the pins.

6. In apparatus for producing an imitation pigskin design in article leather, a frame, a stationary horizontal plate having upstanding sharp-pointed impression pins upon which the leather is laid, a reciprocating pressure roll movable on the frame in a fixed path above the plate for depressing the leather upon the pins, and means mounting the plate in the frame with the pointed ends in spaced relation to the operative plane of movement of the surface of the pressure roll.

7. In apparatus for producing an imitation pigskin design in article leather, a frame, a stationary horizontal plate in the frame having upstanding sharp-pointed impression pins upon which the leather is laid, a pressure roll for depressing the leather upon the pins, a truck supporting the roll for movement above the plate in pressure contact with the leather, supporting means for the truck in the frame preventing pressure contact of the roll with the points of the impression pins, and means for reciprocating the truck.

8. In apparatus for producing an imitation pigskin design in article leather, a frame having opposing side rails, a horizontal plate mounted in the frame between said rails and having upstanding sharp-pointed impression pins upon which the leather is laid, a pressure roll for depressing the leather upon the pins, a truck rotatably supporting the pressure roll, and rollers engaging the upper and bottom portions of the

frame side rails mounting the truck for reciprocation over the plate.

9. In apparatus for producing an imitation pigskin design in article leather, a frame, a stationary horizontal plate in the frame having upstanding sharp-pointed impression pins upon which the leather is laid, a rotatable pressure roll mounted on the frame for reciprocation above the plate for depressing the leather upon the pins, means for rotating the roll, and coacting gear and rack means on the roll and frame responsive to rotation of the roll to cause movement of the roll across the platen and prevent relative slippage between the roller and platen.

10. In apparatus for producing an imitation pigskin design in article leather, a frame, a stationary horizontal plate in the frame having upstanding sharp-pointed impression pins upon which the leather is laid, a rotatable pressure roll mounted on the frame for movement above the plate for depressing the leather upon the pins, means for rotating the roll, and means responsive to rotation of the roll for moving the roll along the frame comprising rack means on the frame and coacting gear means secured to the roll.

11. In apparatus for producing an imitation pigskin design in article leather, a frame, a horizontal impression plate in the frame upon which the leather is laid, a pressure roll above the plate for depressing the leather upon the plate, means mounting said plate and roll in the frame for relative reciprocatory movement, and a flexible blanket unwinding from and winding upon the pressure roll under rotation of the roll in opposite directions automatically laid upon the leather beneath the roll, and removed from the leather, in response to said reciprocatory movement.

12. In apparatus for producing an imitation pigskin design in article leather, a frame, a stationary horizontal impression plate in the frame upon which the leather is laid, a reciprocating pressure roll movable on the frame in a fixed path above the plate for depressing the leather upon the pins, and a flexible blanket secured at one end to the pressure roll and secured at its other end to the frame to be laid upon the leather in the course of movement of the roll.

13. In apparatus for producing an imitation pigskin design in article leather, a frame, a stationary horizontal impression plate in the frame upon which the leather is laid, a pressure roll for depressing the leather upon the plate, a reciprocating truck movable forward and backward on the frame mounting the roll for rolling movement above the plate, and a flexible blanket secured at one end to the frame and laid upon and removed from the leather in the forward and backward movement of the roll truck.
